LIQUID DISPENSER

Lucille R. Marsh and Ione E. Kofoed, Eau Claire, and
Donna Jean Darnutzer, Madison, Wis.

Application October 23, 1958, Serial No. 53,100

Term of patent 14 years

(Cl. D2—3)

The figure is a perspective view showing the top, front and one end of a liquid dispenser embodying our new design.

The end opposite that shown is a mirror image of the end shown and the rear of the dispenser is substantially plain. The dominant features of our design reside in the portion shown in full lines.

We claim:

The ornamental design for a liquid dispenser, as shown and described.
